UNITED STATES PATENT OFFICE.

ALICE LOUISE MARGUERITE CALDWELL, OF NEW YORK, N. Y.

LAMP SHADE AND THE LIKE.

Application filed September 1, 1925, Serial No. 53,794, and in Great Britain January 21, 1925. Renewed February 13, 1929.

This invention relates to lampshades and the like of the kind in which a covering of textile fabric, paper, parchment or the like is mounted on a framework of a convenient form.

The framework for lampshades of this kind usually comprises a rigid structure generally formed of a series of lengths of wire bent to suitable form and soldered together, and if such framework is to be covered with silk or other textile fabric, the wires thereof are wrapped with tape or strips of suitable material to which the fabric cover is attached by sewing.

15 The covering of such shades is a somewhat difficult and lengthy operation and consequently the recovering or alteration of such shades to suit changes in the general character of the decoration of the rooms in which 20 they are used, or the dismantling of such shades to effect the cleaning of the covering material thereof is very rarely effected.

One of the objects of the present invention is to provide a collapsible framework 25 from which the covering may be readily detached and to which it may be readily applied.

A further object of the invention is to provide a framework which may be adjustable 30 in size.

A further object of the invention is to provide a framework of which the various parts thereof may be adjusted to vary the shape of the framework.

35 In order that the invention may be clearly understood reference is made to the accompanying drawings which illustrate by way of example various embodiments of my invention and in which:

40 Fig. 1 is a perspective view of a lampshade according to a preferred form of my invention the covering being shown removed from the greater part of the framework so as to clearly show the construction thereof.

45 Figs. 2 and 3 are respectively front and side elevations of the stay members illustrated in Fig. 1 of the drawings which are adapted to space apart the rings on which the material of the shade is mounted.

50 Figs. 4 and 5 are respectively front and

side elevations of a modified form of stay member.

Figs. 6 and 7 are respectively front and side elevations of a modified construction of the end portions of the stay members by 55 which they are connected to the fabric carrying rings.

Figs. 8 and 9 are respectively plan and front elevation of a fabric carrying ring.

Figs. 10 and 11 are respectively plan and 60 front elevation of a portion of a modified construction of fabric carrying ring.

Fig. 12 is a front elevation of an adjustable support for mounting the shade on a lamp bracket or the like.

Figs. 13 and 14 are respectively plan and front elevation of a modified form of adjustable support with parts thereof removed.

Figs. 15 and 16 are respectively plan and 70 front elevation of a further modified form of adjustable support.

Fig. 17 is a perspective view of an attachment for a lamp support adapted to allow of a ready attachment of a lampshade to its support.

75 Fig. 18 is a diagrammatic view illustrating a compound shape of shade which can be made according to my invention.

Referring to Fig. 1 of the drawings the simple form of framework illustrated therein 80 comprises two collapsible members 1 and 2, of ring like formation, i. e. circular, elliptical, or other closed shape, which are spaced apart by means of a plurality of stay members 3, which, for the small size of lampshade 85 as illustrated, are three in number but which for larger lampshades may be four or more.

The stay members are not rigidly attached to the rings 1 and 2 but are merely in detachable engagement therewith and such rings are 90 held in engagement with such stay members by means of the material 4, which is connected at its opposite sides respectively to the said rings 1 and 2. The material 4 which may be

of silk or other textile material or of paper 95 or the like is suitably shaped according to the form of shade which it is intended to cover. If the lampshade is cylindrical then the material will comprise a straight length of material with its upper and lower sides of a 100

length corresponding to the circumference of the shade. If the lamp shade is the shape of a frustum of a core as illustrated in Fig. 1, then the material will preferably be of sector 5 shape with its upper and lower sides of lengths corresponding to the circumferences of the upper and lower rings 1 and 2 respectively, though such a shape is not essential since if desired the material may be of the 10 same shape as for a cylindrical shade in which case it would be pleated to a greater extent about the upper ring 1 than about the lower ring 2. The collapsible rings 1 and 2 are divided or split transversely, their ends being 15 adapted to be connected together in any suitable manner, and the opposite sides of the material 4 are so formed that they may be attached to the split rings. If the material when mounted upon the frame is intended 20 to be pleated the material at each side thereof may be provided with a series of holes by which it may be threaded onto the rings, one hole being provided in each side of each pleat. Preferably however each side of the 25 material is provided with a fairly broad hem through which the split rings 1 and 2 are threaded. The material is of such a length that when fixed on the frame, the opposite ends 5 thereof contact, thus forming a complete covering for the frame.

The stays 3 are preferably of resilient material and adapted when engaging the rings 1 and 2 to press them apart thereby stretching the material 4 attached thereto and insuring secure engagement between the stays and rings.

The preferred form of stay is illustrated in greater detail in Figs. 2 and 3 of the drawings, and comprises two pieces of resilient 10 strip metal 6 and 7 bound together at their central portions by rivets or by a metallic sleeve or the like 8 encircling the same. The ends 9 of said members 8 are preferably bent inwardly a slight amount so that they will engage the rings 1 and 2 at a great angle and such ends are each provided with a recess 10 which recesses are adapted to receive the rings when the stays are placed in engaging 15 position therewith. The ends 9 engage the rings 1 and 2 through the material 4 when the rings are enclosed in the hems formed on the sides of the material and to prevent any damaging of such material such ends are preferably tapered slightly and the corners of same 20 are rounded off as shown in Fig. 3 of the drawings. If desired such ends may be provided with protecting clips of thin metal such as brass. When applying the stays to the rings 1 and 2 the pairs of legs on the opposite 25 sides of the central binding member 8 are opened out when the ends can be readily engaged with the two rings 1 and 2.

The modified form of stay illustrated in Figs. 4 and 5 of the drawings is adjustable in 30 length and is also preferably made of resil-

ient metal. Any means may be adopted for making the stay adjustable but in the construction illustrated the stay is made in two parts the shank pieces 11, 12 being in sliding engagement with each other and held in such 70 engagement by means of tongues 13 provided in the ends of such shank pieces and embracing the opposed shank pieces respectively. To facilitate engagement and disengagement of such parts recesses 14 are provided in the shank pieces adjacent the tongues 13, such recesses being of a size which will allow of the passage therethrough of the overlapping portions of the tongues when the stay is extended to its limit with the tongues on the opposed shanks adjacent each other. To prevent slipping between the two opposed shanks a screw 15 is provided in screw threaded engagement with one of the shanks and adapted to engage the face of the other shank 75 when operated, though any other well known means may be adopted for this purpose.

The outer ends of the shanks are preferably bifurcated and the ends of such bifurcated portions are so shaped that they are adapted to readily engage the inner edges of the two rings 1 and 2. The shape of such ends may be as illustrated in Fig. 5 of the drawings, the metal of the stay being bent to form a recess 16 which is adapted to receive the ring, such recess being defined by a forward upwardly extending portion 17 and a rearward upwardly extending portion 18. The upwardly extending portions 18 are preferably bent forward at their upper ends so as to tend to retain the fabric carrying ring in the recess 16 and the metal strip is preferably returned upon itself to provide a rounded front edge which will not damage the material. The space between the member 17 and the forwardly extending portion 18 must of course be sufficient to allow of the insertion of the material carrying ring with the material thereon.

In order to facilitate the insertion of the material carrying rings in the recesses 16 and to remove same therefrom the rear wall 18 of such recess with its overhanging portion may be pivotally mounted on the stay as clearly shown in Figs. 6 and 7 of the drawings. In such a construction the material of the stay is bent to form the forward upwardly extending portion 17 and returned upon itself forming the shoulder 19. The end portion at a distance below such shoulder is divided so as to form two spaced portions 20 which are bent about an axis to form bearings for two side projections 21 on the member 22 which defines the rear side of the recess 16. The member 22 is held in its upright position by a spring 23 fixed at its lower end to the body portion of the stay as by rivets and engaging at its upper portion against a flat portion on the member 22. A hole 25 is provided in the member 22 adjacent the upper 120 125 130

end of the spring 23 to allow of such member being turned rearwardly about its pivots when assembling or dismantling the shade.

The rings 1 and 2 may be made of strip metal or of wire. In Figs. 8 and 9 a ring has been illustrated composed of strip metal. Such ring is adjustable in size and is adapted to be readily broken and reformed. For this purpose each end of the ring on the sides thereof is provided with two tongues 26 adapted to embrace the material of the ring to the rear of the other end thereof. In order to break or assemble the ring, recesses 27 are provided in the side edges of the ring adjacent the tongues 26 such recesses being of a depth corresponding to the amount by which the tongues 26 overlap the edges of the ring in engaging same. The outer corners of the overlapping tongues 26 are preferably rounded off as shown in Figs. 8 and 9 so as to allow freedom of movement of the end of the ring within the hem on the covering material 4.

In Figs. 10 and 11 a ring composed of metallic wire is illustrated such ring having fixed at one of its ends as by soldering or welding, a sleeve 28 which provides a passage adjacent the end to which it is fixed through which the other end of the wire ring may be passed, whereby the ring may be broken down or the size thereof adjusted. A second sleeve 29 is also provided which is slideable on the ring and which is of a size adapted to embrace both ends of the ring whereby it may be used for anchoring the free end of the ring to the body portion thereof. The rings 28 and 29 preferably have their ends tapered or rounded as shown in the drawing whereby they will offer as little interference as possible to the assembling of the fabric thereon.

Any suitable means may be provided for connecting the shade to the lamp or to its support. Fig. 12 illustrates means specially adapted to be used in connection with the construction of shade illustrated in Fig. 1 of the drawings. Such means comprises three members 30 preferably made of wire which are adjustable in length each of which is shaped at one end into an annular member 31 adapted to cooperate with the lamp support and at the other end into an upstanding pin like member 32 adapted to engage within a socket 32^a provided for instance in each of the binding members 8 of the stays 3. The adjustability of the members 30 is effected by making them in two parts. Each of such parts comprises a stem 33 and such parts are connected respectively at their outer ends to the members 31 and 32 and are held in sliding engagement relatively to each other by the inner ends thereof being bent over as at 34 so as to encircle the adjacent stem. The stem portions 33 of the members 30 are preferably inclined relatively to the plane of the end portions 31, the direction of inclination

depending upon whether the shade is to be used on a depending light globe or otherwise.

Figs. 13 and 14 illustrate supporting means specially adapted for the type of stay illustrated in Figs. 4 and 5 of the drawings. Such supporting means comprises a central annular portion 35 having a plurality of arms 36 radiating therefrom. Such arms are of strip metal and are in sliding engagement with members 37 of similar strip metal and held in such engagement by means of the tongues 38 on the inner and outer ends respectively of the members and arms, which engage the opposed body portions of such members. The outer ends of said members 37 are provided with claw like members 39 preferably of circular cross section and such claw like members are adapted to embrace the upright portions of the stays 11. In order to readily attach such arms to the said stays recesses 40 (as clearly shown in Fig. 4) are provided in opposite sides of said upright portion thereof of a depth to allow of the open ends of such claw like members passing therethrough. At a short distance from said recesses and at opposite sides thereof shoulders 41 and 42 are provided which are adapted to limit the sliding movement of the stay within the claw like members and to rest against such members and thereby support the shade thereon. The shoulders 41 are provided so that the shade may be used with a depending lamp bulb and the shoulders 42 are provided so that the shade may be used with an upright bulb in which case the end of the stay member provided with the members 41 and 42 will be in engagement with the lower ring. The claw like members enclose a space which is somewhat broader than the thickness of the stays and owing to such members being of circular cross section they can readily engage the stay members whether they are vertical or inclined.

A further modified form of supporting member is illustrated in Figs. 15 and 16 of the drawings. In this form the outer ends of the arms are provided with a hook shaped end 45 adapted to engage under one of the rings of the shade. The length of such arm may be made adjustable as by making it in two parts 46, 47, one of which is adapted to slide within the other. The inner ends of such arms 40 comprise ring shaped members 48. The arms may be inclined relatively to the plane of the ring shaped members or not as is desired.

If desired the ring shaped members on the supporting means illustrated in Figs. 12-16 may be dispensed with and depending pin like members connected to the inner end of each of the radially extending arms may be substituted therefor, in which case a member, such as that illustrated in Fig. 17, containing a plurality of sockets 49, for the re-

ception of such pin like members may be clamped to the lamp standard.

If the shade is to be covered with fairly stiff pleated material the stay members could 5 be made of wire, such members being made adjustable in length in the manner described with reference to Fig. 12 of the drawings and having their ends bent so as to engage the inner edges of the annular members.

10 Though I have described annular members for attaching to the covering material of the shade, which are of an adjustable nature and which are split transversely these features of such members are not essential since 15 such members may be in the form of embroidery ring that is they may comprise two rings one fitting within the other in frictional engagement with each other. With rings of this kind the opposite sides of the material 20 could be respectively securely clamped by two of such double rings and such double rings spaced apart with the covering material in tension, by stay members of the kind previously described. Preferably however 25 the engaging ends of such stay members would be slightly modified to more effectively engage with such double rings, for instance such ends could be made so as to fit snugly around the inner edge of each of the 30 double rings the material being clamped between the double rings so as to extend over the outer edge of the outer rings thereby fully covering such rings. In such a construction there would be no possibility of 35 damage being caused to the material by the stay members since they would engage the clamping rings directly.

It will be appreciated from the description hereinbefore contained that the shade may 40 be readily attached to and detached from the lamp support and that it may be readily disassembled and the parts thereof broken down so as to allow of the ready detachment of the covering.

45 Further, in most of the constructions described the parts thereof including the means for attachment to the lamp shade are adjustable in size so that when the shade has been dismantled they may be adjusted and 50 assembled again to form a shade of different size or shape. The stays illustrated in Figs. 1-3 of the drawings are not actually adjustable in size though their resiliency is such that they will allow of a considerable variation in 55 the width of the material used in covering the shade.

By altering the size of one ring to a greater extent than the other the frame may be changed from a cylindrical shape to that of 60 a frustum of a cone or vice versa, or the slope of the sides thereof may be altered. Further three rings could be combined and spaced apart by two series of stay members to form a frame of the shape illustrated in Fig. 18 of 65 the drawings, and the slopes of the sides

thereof may be altered as desired by adjusting the sizes of the three rings.

If desired the stay members may be covered with material as by wrapping them with tape such material being of a color which harmonizes with that of the material of the shade. 70

If the frame it to be used with a covering of stiff material such as cardboard or the like the rings 1 and 2 may be channel shaped so as to engage about the opposite sides of the material and such rings could be held together by stay members of the kind illustrated in Figs. 4 and 5 of the drawings but having their ends in the form of hooks or the like adapted 75 to engage over the outer sides of such rings. 80

Numerous modifications could be devised in embodying my invention in practical structures, and I do not wish to be limited to the constructions illustrated or described in this specification but desire to cover all embodiments coming within the scope of my 85 appended claims.

What I claim is:—

1. A collapsible framework for a lamp shade comprising a plurality of members of 90 ring like formation adapted to be connected to the covering material of the shade in such manner that they may be readily detached therefrom and attached thereto, and a plurality of stay members to be spaced apart peripherally of the assembled frame, adapted 95 to be detachably engaged to said members of ring like formation when connected to said covering material and to co-operate with said covering material to hold said members of 100 ring like formation in spaced relation.

2. A collapsible framework for a lamp shade comprising a plurality of annular members adapted to be connected to the covering material of the shade in such manner that they may be readily detached therefrom and attached thereto, and a plurality of stay members to be spaced apart peripherally of the assembled frame, such stay members being 105 adjustable in length and adapted to be detachably engaged to said annular members when connected to said covering material and to co-operate with said covering material to hold said annular members in spaced relation. 110

3. A collapsible framework for a lamp shade comprising a plurality of annular members split transversely and adapted to be connected to the covering material of the shade by engagement within a plurality of hems spaced apart in said material and a plurality 115 of stay members to be spaced apart peripherally of the assembled frame, adapted to have their opposite ends respectively detachably engaged to said annular members when connected to said covering material and to co-operate with said covering material 120 to hold said annular members in spaced relation. 125

4. A collapsible framework for a lamp shade comprising a plurality of annular mem- 130

- bers split transversely and having their ends adjustably connected to each other in such manner that such annular members may be adjusted in size, such members being adapted 5 to be connected to the covering material of the shade by engagement within a plurality of hems spaced apart in said material and a plurality of stay members to be spaced apart peripherally of the assembled frame, adapted 10 to be detachably engaged to said annular members when connected to said covering material and to co-operate with said covering material to hold said annular members in spaced relation.
- 15 5. A collapsible framework for a lamp shade comprising a plurality of members of ring like formation adapted to be connected to the covering material of the shade in such manner that they may be readily detached 20 therefrom and attached thereto and a plurality of stay members to be spaced apart peripherally of the assembled frame, such stay members being adjustable in length and having bifurcated ends which are adapted to be detachably engaged to said members of ring like 25 formation when connected to said covering material, said stay members when adjusted into extended position being adapted to co-operate with said covering material to hold 30 said members of ring like formation in spaced relation.
6. A collapsible framework for a lamp shade comprising a plurality of annular members which are split transversely so that 35 they may be connected to the covering material of the shade by insertion in hems provided in said covering material in spaced relation and a plurality of stay members to be spaced apart peripherally of the assembled 40 frame, such stay members being adjustable in length and having bifurcated ends which are adapted to be detachably engaged to said members of ring like formation when connected to said covering material, said stay 45 members when adjusted into extended position being adapted to co-operate with said covering material to hold said members of ring like formation in spaced relation.
- 50 7. A collapsible framework for a lamp shade comprising a plurality of annular members adapted to be detachably engaged to the covering material of the shade and a plurality of stay members adapted to be detachably engaged to said annular members and to co-operate with said material to hold said annular members in spaced relation, said stay 55 members each comprising two resilient members of strip metal lying face to face and connected together substantially at their centers, such resilient members being provided at their ends with recesses by which said members are adapted to engage said annular members.
- 60 8. A collapsible framework for a lamp shade comprising a plurality of members of ring like formation adapted to be connected to the covering material of the shade in such manner that they may be readily detached therefrom and attached thereto, a plurality of stay members to be spaced apart peripherally of the assembled frame, adapted to be detachably engaged to said members of ring like formation when connected to said covering material and to co-operate with said covering material to hold said members of ring like formation in spaced relation, and means adapted to be detachably connected to the assembled frame for connecting the shade to a lamp bracket or the like.
9. A collapsible framework for a lamp shade comprising a plurality of annular members adapted to be detachably engaged to the covering material of the shade, a plurality of stay members adapted to be detachably engaged to said annular members and to co-operate with said material to hold said annular members in spaced relation, said stay members each comprising two resilient members of strip metal lying face to face and provided at their ends with recesses by which said members are adapted to engage said annular members, and a piece of strip metal adapted to embrace said resilient members substantially at their centers for anchoring them together such strip metal being bent to form a socket adapted to receive a pin or the like, and adjustable means adapted to connect said shade to a lamp bracket or the like such means having at its outer ends upstanding members adapted to engage within the sockets on the stay members.
- In testimony whereof I affix my signature.
ALICE LOUISE MARGUERITE CALDWELL.
